UNITED STATES PATENT OFFICE.

BENJAMIN N. BLISS, OF WALTHAM, MASSACHUSETTS, ASSIGNOR TO WALTHAM WATCH COMPANY, OF WALTHAM, MASSACHUSETTS, A CORPORATION OF MASSACHUSETTS.

DESIGN FOR A TIMEPIECE-DIAL.

53,110.

Specification for Design.

Patented Mar. 25, 1919.

Application filed December 5, 1918. Serial No. 265,474. Term of patent 14 years.

To all whom it may concern:

Be it known that I, BENJAMIN N. BLISS, a citizen of the United States, residing at Waltham, in the county of Middlesex and State of Massachusetts, have invented a new, original, and ornamental Design for a Timepiece-Dial, of which the following is a specification, reference being had to the accompanying drawing, forming part hereof.

The figure is a plan view of a watch dial showing my new design.

I claim:

The ornamental design for a timepiece dial, as shown.

In testimony whereof I have affixed my signature.

BENJAMIN N. BLISS.
